Patented Mar. 9, 1920.

Inventor,
Arthur R. Mutton, by
G. B. Kennedy,
Attorney.

UNITED STATES PATENT OFFICE.

ARTHUR R. MUTTON, OF WATERLOO, IOWA.

REGISTRATION-CARD.

1,383,439.

Specification of Letters Patent.

Patented Mar. 9, 1920.

Application filed January 26, 1917. Serial No. 144,739.

To all whom it may concern:

Be it known that I, ARTHUR R. MUTTON, a citizen of the United States of America, and a resident of Waterloo, Blackhawk county, Iowa, have invented certain new and useful Improvements in Registration-Cards, of which the following is a specification.

My invention relates to improvements in registration cards, and the object of my improvement is to supply related registration spaces and selective indicative means on such a card, adapting it for use in connection with meter registering devices or the like.

15 This object I have accomplished by the sub-divided patterned card shown in the accompanying drawing, and which is herein-after described and claimed.

The card shown is particularly arranged 20 for use in the impressing, puncturing or otherwise recording upon it indicative signs or data by means of special mechanism on a meter registering device, such as a meter for automatically measuring electrical current, water or gas.

For this purpose the card may have one face sub-divided as shown, into a plurality of separated spaces to receive related data or other information desired.

30 The card may be of any shape or size, but as shown, is oblong, and has printed or otherwise displayed on its ends 4 the duplicate rows of circles 5, each circle having therein an annular concentric row of successive numerals usually in a decimal series, with numerals just without indicative of the ascending decimal multiples of the successive series, and with the numerals in the circles alternately reversed in relative positions 35 to properly correspond with card piercing means carried by the gear mechanism of the meter in the registering device in which the card is placed for a record to be made thereon. An inclosed space 2 may be provided 40

45 midway along one longitudinal edge of the card, to receive directions for using the card. A blank space 1 is left directly opposite the inclosed space 2, and may be employed to receive the name and address of the user of 50 the meter. Spaces are left between the meter registration circles 5 and the said middle spaces 1 and 2, to receive die impressed embossed numerals 3 adjacent to printed

words "Number" at 7 giving the identifying number of the meter. These embossed numerals may be impressed on the card by the registering device to accompany punctured or slotted records 6 on the numerals within the circles 5, whereby there is preserved on the card a complete registration of the condition of the meter current measuring means at the instant of registration, with means for identifying the particular meter.

55 My registration card is of course complete for a single registration, if made with but a single set of registration circles 5, but I have provided a duplicate set of these circles on the other end of the card, so that one card may be employed to take registrations from two meters used by one person, or to take 60 two readings from the same meter.

65 These different compartments or registration spaces may be otherwise displayed or arranged on the card without departing from the principle of my invention, since it 70 is my purpose to have them properly conform to the requirements for use in the particular registering device, without being arbitrarily confined to the special means shown.

75 Having described my invention, what I claim as new, and desire to secure by Letters Patent, is:

1. A perforable record card for meters, the same consisting of a leaf having a 80 printed representation along one end of the dials of a meter omitting the indicators; having adjacent thereto a reserved space and a printed designation for the characters to be embossed upon the reserved space, and also having on the same face a printed notice and a space for a name and address; said printed dials being perforable by perforating indicators on a meter, and the said reserved space being adapted to be embossed 85 simultaneously with the meter number.

2. A perforable duo-record card for meters, the same consisting of a leaf having printed representations along opposite ends of the dials of a meter omitting the indicators; having adjacent both sets of said printed dials reserved spaces to receive embossed numerals; having between said spaces another space to receive a name and address; each set of printed dials being adapted for 100 independent simultaneous perforation of all 105

the dials therein, and the embossing of the numeral in each reserved space being simultaneous with the perforating of the set of printed dials adjacent thereto, the sets of 5 dials at opposite ends of the card being arranged in inverse relation with regard to each other.

Signed at Waterloo, Iowa, this 23d day of January, 1917.

ARTHUR R. MUTTON.
